UNITED STATES PATENT OFFICE

GEORGE M. PORTER, OF NEW YORK, N. Y.

PRINTING PRESS

Application filed June 8, 1931. Serial No. 542,766.

The present invention relates to what is known as flat bed printing presses in general, and particularly to the inking mechanism of such presses and especially to the construction of such inking mechanism.

According to the present invention, the paper stock can be either doubled, tripled, or quadrupled, in size desired according to the number of colors to be printed in the one operation and all colors run in one form thus filling the press to capacity and then turning the sheets around and printing again for one color to interlap into the other. By the methods at present in use, the press could only be run to capacity by multiplying the number of electrotypes for each color and run each color separately, but the cost of the additional electros for each color and the locking up of larger or capacity forms, the makeready and the registering of a greater number of electros become prohibitive and therefore rather small sheets are handled.

According to the present invention any single color letter press can easily be converted into a multicolor press at a small cost, and should it be desired to print only one color after the press is so converted, all the ink fountains may be filled with the same one color ink and printing may be done as usual.

One of the objects of this invention is to provide in connection with a flat bed cylinder type of printing press or in fact with any letter press an inking apparatus for facilitating the application of distinct sections, blocks or columns of ink simultaneously to the inking and form rollers, thereby enabling the printing of a sheet in different parts of various colors or in inks of different consistencies by a single impression.

In order to accomplish the above results, the ink fountain is divided into compartments by means of removable partitions; the ink plate of the printing press is divided by a number of longitudinally arranged, parallel recesses, corresponding in number to that of the fountain divisions, and the steel ink distributing rollers, in contact with what is known as the form rollers or composition rollers are also provided with divi-

sions or recesses, corresponding also in number to the divisions of the fountain.

By means of the above provisions, which may be varied, as to their number and arrangement depending upon the necessary requirements for different types and sizes of work and of presses, it is made possible to transfer different colorings simultaneously upon the type or the form from which the ink is transferred to the sheet to be printed.

Another object of my invention is to provide in connection with a flat bed, cylinder printing press equipped with reciprocating, sectionally divided distributing rollers, suitable means whereby the divisions of such rollers may be eliminated, so that such distributing rollers assume the appearance of and become, to all intents and purposes, continuous solid distributing rollers.

Another object of my invention is to provide in connection with the divided ink plate of a letter printing press means whereby the recesses of the ink plate may be filled at will so as to enable the use of the plate in the same way as if it were made with a solid, uninterrupted surface.

Heretofore, in attempts to obtain results described herein, printers would cut grooves in the composition rollers for the purpose of spacing ink areas, but this operation is very costly and renders the composition rollers useless for the next job; such operation likewise consumes considerable time and skill and also the groove so cut must be quite wide in order to keep the inks from mixing. This extra width also requires the use of wider stock, thus further increasing the cost of the job.

The foregoing and still further objects of my invention will become more fully apparent from the following description and the accompanying drawings, forming part of my disclosure, and although the same illustrates an embodiment of the invention as applied to flat bed cylinder type of printing press, it is by no means intended to be limited to the actual showing, and in which:

Fig. 1 is a plan view of a conventional flat bed cylinder printing press, including an embodiment of the invention.

Fig. 2 is a cross-sectional view through such conventional printing press taken on line 2-2 of Fig. 1.

Fig. 3 is a partial, enlarged detail top view of a flat bed printing press showing an arrangement of the improvements in the ink plate and in the steel distributing rollers.

Fig. 4 is a partial end elevation, in enlarged form, of a transfer roller and a distributing roller as seen when looking in the direction from the ink fountain.

Fig. 5 illustrates an enlarged detail view of a removable partition adapted to divide the ink fountain into compartments.

Fig. 6 is an enlarged detail cross-sectional view of a distributing roller equipped with a fill-in member.

Fig. 7 is a partial cross-sectional view illustrating a fill-in member provided in the groove of the ink plate.

Fig. 8 is a cross sectional view through an alternate form of ink plate having removable and interchangeable ink receiving sections.

All illustrations above enumerated are more or less diagrammatic and are intended to serve rather for experiment purposes than for showing structure. In the drawings, numeral 10 denotes a conventional type of ink plate of a printing press, usually provided with a form section indicated at 11 and an inking section 12, which latter is ordinarily provided with a smooth upper face. For the purpose indicated above, the ink carrying portion is divided into distinct fields 13 by means of dovetailed grooves 14, the number of which depends upon the number of colors or fields it is desired to be produced for such a press.

At the right hand end and below the ink plate is arranged an ink fountain, indicated at 15, of conventional construction and provided with a fountain roller 16 which in this case has its otherwise smooth surface provided with a plurality of grooves 17, which divide the roller into distinct portions or sections.

In engagement with grooves 17 of ink fountain roller 16 are partitions 18, shown in detail in Fig. 5. The roller engaging portion 19 of the partitions is curved so as to correspond to the annular recess within the roller, while at the opposite end there are provided attaching means 20 by which the partitions are secured to the fountain structure, as may be clearly observed from Fig. 2.

These partitions divide the fountain into distinct compartments which may be filled at will with inks of different consistencies or of different colors. While I have shown three partitions provided in an ink fountain, which is thus divided into four compartments, it is obvious that a greater or lesser number of such partitions may be arranged, and that

the partitions may be easily removed for the purpose of cleaning the fountain.

Adapted to alternately contact with fountain roller 16 and plate 12, there is provided an ink transfer roller or ductor 19 which is pivoted at 20' (see Fig. 2) and which is designed to once engage with and take ink from a roller 16, as shown in Fig. 2, in full lines, and at the next moment to deliver the ink to the upper surface of the ink plate, as indicated in broken lines. This arrangement is not new and is of conventional structure and therefore need not be further explained, since its function as transfer agent for the ink from the fountain roller to the upper surface of the ink plate is well known in the art.

Above the plate there are shown four groups of rollers consisting of a pair of ink pick-up or delivery groups at the right end of the plate, and form-inking rollers arranged substantially at the center of the plate. Both groups comprise composition rollers 21, in contact with the plate and ink-distributing rollers 22, in contact with the composition rollers. These ink-distributing rollers are preferably made of steel and are so arranged that besides revolving, which rotation is caused by the movement of the plate, the steel rollers are caused to reciprocate longitudinally. This reciprocation is accomplished by an arrangement of cranks indicated at 23 in Figs. 1 and 3.

It will be observed that steel rollers 22 are provided with annular recesses 24 corresponding in number to the number of recesses in the fountain roller and to the number of recesses 14 provided in the ink plate. It will be further observed that the recesses 24 are as wide as recesses 14, provided in the plate so that although rollers 22 reciprocate their movement will not exceed the widths or cause them to travel beyond the edges of recesses 14.

In near proximity of the left hand group of rollers is provided a conventional cylinder 25 adapted for the delivery of sheets to be printed and pressed against the type contained in form 11.

Whenever it is desired to print less than four distinct columns, as is possible with the arrangement shown in Figs. 1 and 3, the steel distributing rollers 22 may be filled by means of split rings as shown in detail in Fig. 6 and indicated at 26, as to present a smooth cylindrical surface where desired. These rings are preferably formed of two halves which are hinged together at one of their ends, as shown at 27, while the other ends are preferably offset at 28 and 29 and provided with suitable locking means, whereby they are held together and to the roller. Similarly, grooves 14 of the plate have to be filled, which is accomplished by means of dovetailed inserts shown at 30 in Fig. 7, and which are held in the plate by any suitable means, as for instance a screw, indicated at 31.

The function of the device becomes readily evident from the foregoing description. When it is desired to print sheets in different colors or different shades, or with inks of different consistencies, the desired number of grooves of the distributing rollers and ink plate are freed of their respective filler members, and the ink fountain is supplied with the desired inks in each of the compartments.

As the plate travels in right hand direction, as indicated in broken lines in Fig. 2, the different inks are supplied from the fountain roller by means of the ductor roller 19 to the plate surface, from which latter the first right hand group of composition rollers pick-up the ink which is thoroughly distributed over their surfaces by means of the respective surface of the reciprocating steel roller which is continuously in contact with the composition rollers. The ink is transferred through the movement of the plate from the first composition rollers to the next group of rollers and the same operation takes place in that group, while the ink is more thoroughly spread over the plate. As the latter continues in its travel, the ink is brought up to the first roller arrangement at the left hand end of the plate, and through the plate is delivered to the last group of rollers. The two left hand groups of rollers deliver the ink to the form located in the form end 11 of the press from where the ink is transferred to the sheet delivered by cylinder 25.

Due to the fact that rollers 22 are limited in their respective movement and further due to the fact that the plate is divided by relatively broad recesses 14 into distinct sections, the individual ink groups delivered by way of the plate to the rollers are prevented from mixing, whereby each plate section, defined by the plate grooves and steel roller grooves, is individually supplied with its respective ink mixture and thus delivers the latter without overlapping, to the type form, and subsequently to the paper upon which the print appears.

The foregoing description and the elucidated manner of operation of my device deal with specific forms of my invention, as shown in the accompanying drawings.

It is obvious however, that variations, modifications, improvements and changes may be readily incorporated within my device, for the purpose of meeting different requirements which undoubtedly must become necessary when my idea is applied to the different types of presses, intended for lesser or greater speed, and designed for delivery of various classes of printing work. I, therefore, reserve for myself the right to make such changes and improvements, as may become necessary, without departing from the broad scope of my idea comprising the employment of divisions in not only the re-

ciprocating mounted distributing rollers, and the fountain, but also the divisional means provided in the ink plate itself, in the manner and as set forth in the annexed claims.

One modification that I have found effective is to provide an ink plate 10a with raised flanges on its longitudinal edges only and provide sectional inserts 13a equal in thickness to the height of the flanges and of various widths but running the full length of the plate. The sections may be interchanged and moved and adjusted to provide spaces or grooves 14a between them so as to line up with the divisions or grooves in the fountain roller and steel rollers.

I claim:

1. In an inking mechanism for printing presses, the latter including a flat ink plate, an ink fountain, a fountain roller, groups of ink pick-up and form rollers, said groups including distributing rollers; ink fountain separating means removably associated with said ink fountain and said fountain roller, said means comprising rectangular grooves in the bottom wall of the ink fountain, corresponding grooves in the fountain roller and partitions removably but snugly set within the fountain grooves and extending into the fountain roller grooves to effectively prevent commingling of the inks in the respective compartments formed by the partitions, and ink separating provisions arranged with said plate and said distributing rollers.

2. In a printing press of the flat bed cylinder type, a plate having ink separating provisions, an ink fountain and a fountain roller rectangular grooves in the bottom wall of the ink fountain, corresponding grooves in the fountain roller, partitions removably snugly fitting into the fountain grooves and extending into and closely fitting the fountain roller grooves to effectively prevent commingling of the inks in the respective compartments, formed by the partitions, a plurality of groups of ink pick-up and form rollers provided with ink distributing rollers, the latter having provisions for maintaining separate, ink supplied to sections of the pick-up and form rollers whereby different color inks are prevented from overlapping.

3. In a printing press of the flat bed cylinder type, a plate having longitudinal ink separating provisions, an ink fountain and a fountain roller, the former provided with removable ink separating partitions snugly fitting in grooves in the bottom wall of the fountain, the fountain roller being provided with rectangular grooves for accommodating said partitions, a group of pick-up rollers, another group of form rollers, both groups including reciprocatingly mounted ink distributing rollers, the latter provided with ink separating means for preventing the overlap-

ping of different inks delivered to said pick-up and form rollers.

4. In a printing press of the flat bed cylinder type, a plate having longitudinally arranged dovetailed ink-separating provisions, an ink fountain having a fountain roller in operative relation to said plate, said fountain roller being provided with annular rectangular recesses, a plurality of ink separating partitions associated with said ink fountain and in operative engagement with said recesses of the fountain roller, rectangular grooves in the bottom wall of said ink fountain into which the partitions are snugly but removably fitted, a group of ink pick-up rollers and another group of form rollers in cooperative relation with said plate, each of said roller groups including ink distributing rollers, the latter adapted to reciprocate and provided with ink separating, annular grooves or recesses, all of said ink separating means of said plate, said fountain, said fountain roller and said distributing rollers corresponding in numbers to one another.

5. In a printing press of the flat bed type, a plate having longitudinally arranged dovetailed ink separating provisions, an ink fountain having a fountain roller in operative relation to said plate, said fountain roller provided with annular rectangular recesses, a plurality of ink separating partitions associated with said ink fountain and in operative engagement with said recesses of the fountain roller, rectangular recesses in the bottom wall of said fountain, into which the partitions are snugly but removably fitted, a group of ink pick-up rollers and another group of form rollers in cooperative relation with said plate, each of said roller groups including ink distributing rollers, the latter adapted to reciprocate and provided with ink separating, annular grooves or recesses, all of said ink separating means of said plate

said fountain, said fountain roller and said distributing rollers corresponding in numbers to one another, said dovetailed ink separating provisions of the plate having a width greater than the reciprocating movement of the ink distributing rollers, said rollers being so arranged that the length of their reciprocating movement does not exceed the width, and does not permit an over-lap of the ink beyond the edges of said ink separating provisions of the plate.

6. The combination with a printing press of the flat bed type, having a plate provided with ink separating provisions adapted to receive removable filler means, of an ink fountain in cooperation with the plate and provided with a fountain roller, and ink dividing means removably secured in rectangular grooves or recesses in the bottom of said ink fountain, said roller having rectangular recesses for accommodating said ink dividing means.

7. An annular recess filler for rollers used in printing presses, comprising a pair of semi-circular members in hinged connection with one another and provided with locking means for holding them together in the form of a ring.

8. An annular recess filler for ink distributing rollers of printing presses, comprising a pair of hinged members adapted to fill, when closed, an annular ink separating recess of a distributing rollers, and having interlocking ends adapted to be brought together and locked in position within such recess, so as to present a smooth continuous outer surface, corresponding to the unrecessed outer surface of the roller.

Signed at New York city, in the county and State of New York, this 29th day of May, 1931.

GEORGE M. PORTER.
